ABSTRACT OF THE DISCLOSURE

An X-ray generator tube 1 and an ionization detector 2 are disposed in an evacuable enclosure 4 together with a turntable 3 carrying a number of sample mounts *e* around its periphery, and indexable to present each sample in succession at a testing position in which the sample (*e*1) is irradiated with a primary X-ray beam *X* from generator 1 and re-emits a secondary beam *Y* into detector 2, which thereupon generates voltage pulses corresponding in amplitude to the atomic numbers of the chemical elements present in the sample. The pulses are passed through an amplitude discriminator which gates pulses of selected amplitude to a digital counter which counts the gated pulses over a prescribed time interval as an indication of the concentration of the particular element in the sample. Presettable automatic control means index the turntable, adjust the X-ray beam voltage, the gating threshold and width, and counting time, and accomplish auxiliary functions in an automatic cycle.

This invention relates to a method and apparatus for the chemical analysis of samples of material by means of X-rays, and more particularly to non-dispersive X-ray fluorescence mass spectrometers.

The primary object of the invention has been the provision of practical apparatus whereby the quantitative analysis of samples of matter can be conducted with rapidity yet with high precision under shop conditions, for production inspection and similar purposes. A related object is to provide such apparatus which will operate in a fully automatic manner and yet can be programmed with extreme flexibility, e.g. to permit analyzing different samples for different constituent elements, without impairing the automatic character of the procedure. An object is to provide such apparatus which will be compact and strong, easily and reliably operated and serviced by unskilled hands, and foolproof in respect to the hazard of irradiation by the X-ray beam used.

High-energy radiations (such as X-rays) can be used in various ways for the purpose of quantitative chemical analysis (or mass spectrometry) of a sample of material. The common idea underlying all such methods of analysis with X-rays and the like radiations, is to provoke an interaction between the incident or primary beam, and the atoms of the various constituent elements present in the irradiated sample. The incident photons, if sufficiently energetic, excite the atoms in the sample. The atoms of the constituent elements, when thus excited, emit radiations (so-called X-ray fluorescence) at frequencies which are characteristic of the atoms involved. Hence by analyzing the frequency spectrum of the secondary radiation reemitted by the sample as a whole it is possible to analyze the chemical compositions of the sample.

In one class of methods based on this broad principle, the beam of secondary radiation reemitted by the sample is analyzed into its frequency components by selective diffraction through a crystal lattice (using the well-known Bragg spectrometer or similar device). The various fre-

2

quency components in the incident secondary beam are selectively diffracted at various angles, so that by receiving and measuring the amount of radiation diffracted in an appropriate direction the proportion of a corresponding constituent element present in the sample can be determined. This widely used method has serious drawbacks. Although the separating or resolving power of such a diffraction X-ray spectrometer is high (since it is readily possible to distinguish between two diffracted rays separated by a very small angular amount), the sensitivity is poor owing to insertion of the diffracting crystal in the path of the incident (secondary) beam. Also, the inherent geometry of such a spectrometer is such that the solid angle under which the sample is "seen" from the crystal is very small; in other words the instrument is able to analyze the secondary radiation reemitted from only a very small area of the sample. This further reduces the sensitivity and, moreover, increases the influence of the surface condition of the sample. This last would be a grave deficiency in an instrument designed for high-output work under shop conditions. Moreover, instruments of this class are inherently bulky.

The other important class of X-ray fluorescence mass spectrometers is based on the so-called non-dispersive method. Here the entire secondary beam reemitted by the sample is received in a suitable ionization detector of the type usually known as a proportional counter. This is essentially an ionization chamber containing a suitable gaseous atmosphere (e.g. argon and methane) such that each frequency component of the incoming secondary beam, corresponding to an element of particular atomic number present in the sample being analyzed, ionizes or excites a number of gas atoms in the counter proportional to the energy content, i.e. frequency value, of said component. The counter thereupon produces a discharge pulse whose voltage amplitude corresponds with the element of said particular atomic number. By subjecting the pulses produced by the proportional counter to an amplitude discriminating step so as to gate only those pulses whose peak amplitude is within a prescribed range corresponding to the atomic number of a selected element present in the sample and counting the gated pulses over a fixed period of time, it is possible to determine the amount of said selected element present in the sample.

45 This non-dispersive method of X-ray analysis has many advantages. It has good sensitivity, permits of utilizing large solid angles and hence large sample areas thereby minimizing the effect of surface defects, and can be embodied in compact, rugged instrumentation. It has however exhibited a serious inferiority as compared to the diffraction methods in respect of resolving power. Elements of closely similar atomic number produce voltage pulses of closely similar amplitude in the proportional counter, and it has been found difficult and sometimes impossible to perform the amplitude-discrimination gating operation with sufficient fineness to permit of an unequivocal separation between such elements positioned close to one another in the periodic table. This difficulty has been especially great in the case of the lighter elements.

60 It is among the objects of this invention considerably to reduce this defect of non-dispersive X-ray analysis and improve the resolution achievable therewith, thereby to render this otherwise highly desirable method practically appreciable to the accurate quantitative analysis of chemical elements substantially regardless of atomic number.

65 Another object is to provide practical workshop-type apparatus for the automatic quantitative analysis of a large number of samples of material in regard to one or more constituent elements thereof, which will operate on

the non-dispersive X-ray fluorescence principle just outlined, and which will be efficient enough to provide an accuracy amply sufficient for industrial purposes without requiring the pulses from the proportional counter to be counted over inordinately long periods of time, thus enabling the apparatus to keep step with normal production rates.

For example, in the application of the apparatus to the determination of sulfur content in samples of tire rubber in a tire manufacturing plant (this being the specific application for which the invention was originally developed), sulfur contents over a range of from 1 to 6% were measured with a relative precision of 10^{-2} , using count times of 30 seconds per sample.

Exemplary embodiments of the invention will now be described for purposes of illustration but not of limitation with reference to the accompanying drawings, wherein:

FIG. 1 is a general view, partly in simplified elevation, partly in the form of a functional diagram of an X-ray sample analyzer apparatus according to the invention;

FIG. 2 is a simplified view of the apparatus of FIG. 1 in overhead plan, omitting the units shown in functional form in FIG. 1;

FIG. 3 is a diagram of the automatic control circuitry of the invention;

FIG. 4 is a partial diagram illustrating an improved modification of the automatic control circuitry;

FIG. 5 is a view in selectional elevation showing a practical form of construction of the testing unit of the invention in more detail than FIG. 1;

FIG. 6 is a corresponding view in plan;

FIG. 7 is a selection on line VII—VII of FIG. 6, illustrating the movable X-ray shutter device;

FIG. 8 shows a typical experimental graph of pulse-counts-per-second versus peak amplitudes of the voltage pulses delivered by the proportional counter in response to sulfur content in a sample used for calibration purposes; and

FIG. 9 is an experimental graph in which pulse-counts-per-thirty-seconds are plotted versus sulfur content for a number of samples used for calibration purposes.

A general description of the invention will first be given with reference to FIGS. 1 and 2. In FIG. 1, the arrowheaded lines interconnecting various units of the apparatus represent the flow of data and command information between the units. The significance of these interconnections will become fully apparent after the detailed description of the controller unit with reference to FIGS. 3 and 4. Thereafter a practical embodiment of the mechanical section of the apparatus shown in FIGS. 1 and 2 will be described in detail with references to FIGS. 5 to 7. Finally a numerical example of the practical performance of an embodiment of the invention will be given, reference then being made to the graphs of FIGS. 8 and 9.

Referring to the diagrammatic views of FIGS. 1 and 2, an X-ray analysis apparatus according to the invention comprises an X-ray generator tube 1 and an ionisation counter 2 disposed within a pressure-tight enclosure provided by a domed bell-like cover 4 having its base sealingly engaging a flat baseplate or table surface 16. A vacuum connection 17 communicating with the enclosure through the surface of table 16 leads by way of a valve 14 to a suitable vacuum pump 10 driven from a motor M1; valve 14 is operable by a solenoid S1 to vent the interior of enclosure 4 to atmosphere.

Also positioned within the enclosure under bell cover 4 is a rotatable sample-carrier turntable 3 carried on the top of a shaft 18 sealingly journaled in suitable bearings (not here shown) in the table 16. The shaft 18 at its lower end is coupled to be driven from a suitable electric motor M2 supported underneath the table 16. An indexing wheel 8 carried by shaft 18 underneath the

table 16 cooperates with a latch 9 actuated by a solenoid S2 so as to index the shaft 18 and turntable 3 to a number of accurately determined angular positions as will be presently understood. The turntable 3 carries a number of sample mounts uniformly spaced around its periphery. These sample mounts or supports are twelve in number in the illustrative embodiment and may carry respective samples designated e1 to e12. In each of the indexed settings of turntable 3 provided by the indexing arrangement 8-9, a particular one of the samples is located at an analyzing or testing position relative to the X-ray tube 1 and counter 2. In the figures sample e1 is shown in testing position. FIG. 2 also shows the path of a primary X-ray beam X emitted from the anticathode 19 of the X-ray tube 1 towards the sample in testing position through a window 20 in the X-ray tube casing. A beam of secondary radiation indicated at Y in FIG. 2 is reemitted from the sample such as e1 in testing position in response to the primary X-rays striking it, and enters the ionization counter 2.

It is convenient to have the possibility of opening the cover 4 as for recharging the samples on turntable 3 (as later described in detail) without having to cut off the X-ray beam from tube 1. To make this possible without exposing the operator to irradiation, a shutter 5 (omitted from FIG. 1 for clarity) opaque to the X-rays from tube 1 is arranged to be automatically positioned across the X-ray tube exit window 20 whenever the cover 4 is lifted off, and to be removed to a position clear of the window when the cover 4 is replaced. Exemplary mechanism for this purpose is later described.

Before continuing the description, some known theoretical principles of the non-dispersive method of X-ray analysis applied in the invention will be briefly recalled.

As in other methods of X-ray analysis, the method is based on a selective interaction of incident X-ray photons with atomic electrons of the respective elements contained in the target sample. The theory of this interaction is very complex, but for the purposes of this discussion the following simplified picture should suffice. On being hit by X-ray photons of suitably high energy from the beam X (FIG. 1) certain electrons in the irradiated sample such as e1 are knocked out of their normal energy states or orbits and the thus excited or ionized atoms a short time later return to their normal or ground state as the vacant energy states are refilled. In so doing the atoms "fluoresce," i.e. emit rays of a frequency that is a characteristic of the atoms involved. Hence, an analysis of the secondary spectrum reemitted by the target sample e1 can reveal the chemical composition of the sample. In such a spectrum, which is a discontinuous one, the various frequency peaks are indicative of the constituent chemical elements and the amplitudes of the peaks are proportional to the respective concentrations of those elements in the sample.

To effect this analysis the reemitted or secondary beam Y from the sample e1 is received in the ionization counter tube 2. The counter here used is of the continuous gas-flow, proportional type. Devices of this type are generally conventional and their broad principle of operation is the following.

The counter tube has means (not shown) providing a continuous circulation of a gas mixture (e.g. 90% argon and 10% methane) therethrough, at a pressure somewhat lower than atmospheric. The tube contains an axial conductor wire 21 connected to a high positive voltage source so as to create a strong radial electric field from the wire to the grounded periphery 22 of the tube. The beam of secondary rays Y reemitted from the sample enters the tube through a window 23 made of a thin sheet of material transparent to the rays. The photons from beam Y excite the atoms of gas in the tube 2 and, through a rather complex process involving Auger transitions and the Townsend avalanche effect (also known as cumulative or cascade ionization) each incoming photon causes the release of a large number (of the order of e.g. 10^7)

of electrons which are attracted to the positively charged central conductor 21 and produce a corresponding voltage discharge pulse on the output conductor 24 of the counter tube. The duration of such a discharge pulse may be on the order of 0.1 millisecond.

The amplitude of each voltage pulse thus produced on the counter tube output line 24 is proportional to the energy of the incoming photon (from the secondary beam Y) which originated the discharge. Hence said amplitude is a measure of the frequency of the secondary radiation reemitted by the sample e, and therefore (as explained above) an indication of the particular chemical constituent element responsible for the discharge. The rate at which the pulses occur per second is proportional to the amount of the particular constituent in the sample.

Therefore, by counting over a given period of time (say 30 seconds) the number of pulses of various amplitudes present on the ionization detector output line 24, the chemical composition of the sample can be ascertained.

It will be understood that the counter 2 will normally deliver, over a given period of time, irregularly spaced, interspersed series of pulses of the various amplitudes corresponding to the chemical constituents of the sample, with the total number of pulses of each amplitude statistically corresponding to the relative proportions of the constituent elements. Usually, however, it is desired to test for a single constituent element at a time, and for this purpose it is necessary to count only those voltage pulses whose amplitudes lie between certain prescribed upper and lower limits so selected as to include only those pulses corresponding to the desired element. The count obtained will then represent a measure of the amount of that element present in the sample.

To illustrate the above by means of an example, reference is made to FIG. 8 which shows part of a graph in which the abscissa are voltages and the ordinates are pulse counts per second. The graph represents a Gaussian distribution curve of pulse counts corresponding to the atoms of sulfur present in a test sample of graphite used for calibration purposes. It is seen that the voltage spread at mid-altitude of the curve is from $V1=46$ volts to $V2=64$ volts.

This means that if the voltage pulses occurring on the counter output line 24 are amplitude-discriminated and gated so as to pass only those voltage peaks greater than $V1$ and less $V2$ and only the gated pulses are counted, the count per second (or other given time interval) will be proportional to sulfur content in any sample used as a target.

To perform this selective amplitude-discriminative gating function, the line 24 is applied to an amplitude-discriminating unit schematically shown at 11. Unit 11 essentially comprises a preamplifier in which the pulses applied over line 24 are preamplified, and voltage gating means in which the preamplified pulses are compared to selectable upper and lower reference voltage levels $V2$ and $V1$. The unit 11 is schematically shown provided with the two controls 25 and 26, such as potentiometer knobs, which serve respectively to preset the lower or gating threshold voltage (above termed $V1$), and the gate width ($\Delta V=V2-V1$). Adjustment of the controls 25 and 26 can therefore serve to preset the lower and upper limits of the voltage peaks that are allowed to pass from the counter tube output line 24 to the output of the amplitude-discriminator circuit 11. It will be understood from earlier explanations that this dual adjustment makes it possible to pass to the output of circuit 11 only those discharge pulses from the ionization detector or counter tube 2 that represent responses of said counter tube produced by the atoms of a particular element (say sulfur) that it is desired to titrate in the sample e exposed to the X-ray beam X from X-ray tube 1.

The pulses thus selectively gated are passed from circuit 11 to a digital counter circuit 12, such as a conventional decade counter. Counter circuit 12 is shown provided with a control 27 which is adjustable to preset the time interval

over which a count is made. With control 27 adjusted to a given time interval (say thirty seconds), it will be evident that the count indication given by counter circuit 12 for each of the samples e_1-e_{12} positioned at the testing station (as shown for sample e_1 in FIG. 2) will be a function of the amount of the element (say sulfur) selected by means of the amplitude-discriminator controls 25-26, in the particular sample. The count indications given by counter circuit 12 may be recorded in any desired manner, and as here shown said indications are applied to a printing unit schematically shown at 13.

In a non-dispersive X-ray fluorescence method of analysis, of the class to which the process of the invention broadly pertains, a serious problem has existed in connection with the separating or resolving power achievable. The characteristic spectral lines of the secondary X-ray beam (indicated as Y in FIG. 1) reemitted by the atoms of any element present in the specimen and received in ionization counter tube 2, have frequencies that are proportional to the atomic number of the element (Moseley's law). Hence, should the specimen contain constituent elements whose atomic numbers differ by relatively small amounts, the discharge pulses produced on line 24 by the responses of the atoms of such neighboring elements to the primary X-ray beam X will not differ much in their voltage peak values, and there may be difficulty in discriminating between such pulses by adjustment of the threshold and gate-width voltages in the amplitude discriminator circuit 11 (through adjustment of controls 25, 26). This difficulty would be especially serious in connection with elements of relatively low atomic number, that is to say the lighter elements.

In accordance with a feature of the invention, the resolving power of the apparatus is substantially increased and its usefulness for the quantitative analysis of light elements enhanced, by providing as the source of primary X-ray beams an X-ray tube 1 having means for accurately regulating its high-tension supply voltage, and adjusting said voltage to a level high enough so that the resulting primary beam from X-ray tube 1 will be capable of exciting the atoms of the selected element but not so high that said beam will excite any elements of substantially higher atomic number. By this expedient the ionization counter 2 can be prevented from delivering on line 24 any discharge pulses due to the responses of atoms of any heavier elements that may be present in the tested specimen. The task of the amplitude-discriminator 11 is thereby facilitated and its functioning made more effective in that its voltage controls 25, 26 need simply be adjusted to discriminate against those elements present in the sample that are lighter than the selected element.

For this purpose, the voltage supply unit for X-ray tube 1, which is schematically shown at 15, comprises a suitable high voltage power generator together with means for precisely regulating voltage (and current) values of the generated power and means for preselecting said voltage and current values. Controls for preselecting the voltage and current of the high-tension supply 15 are schematically shown at 28 and 29 respectively.

Means are provided in accordance with the invention for automatically controlling the operation of the system so far described in accordance with a prescribed sequence and including flexible means for modifying such sequence. The automatic control or programming means is schematically represented in FIG. 1 as the unit 6, and will now be described in detail with reference to the diagram of FIG. 3.

In this diagram, components designated by the same references as components shown in FIGS. 1 and 2, are to be identified with these latter even though they may be represented by somewhat different symbols. For the sake of both brevity and clarity, the circuitry of FIG. 3 will first be described in its broad lines only, and the disclosure will thereafter be pursued with reference to the operation of the system, the various circuit components being referred to as they participate in this operation.

Connected across the alternating network 100 is the primary winding of a supply transformer 101 having two secondaries 102, 103. Also connected across the network 100 is a motor M3 which serves to drive a fan, not shown, acting to circulate the mixture of argon and methane previously referred to through the continuous-flow, proportional ionization detector or counter 2. A general cut-off switch 104 is connected between one terminal of network 100 and the junction of motor M3 and the primary of transformer 101.

Transformer secondary 102 delivers 220 volts in the example across the A-C supply lines 105, 106. This 220 volt alternating power across 105-106 serves to energize inter alia the following components connected in parallel across said lines:

Vacuum pump motor M1 which drives the vacuum pump 10 (FIG. 1) for evacuating the enclosure under bell cover 4;

Solenoid S1 serving (when deenergized) to operate the valve 14 to cut off the vacuum connection and vent the enclosure 4 to atmosphere instead.

Turntable motor M2 which through indexing gear 8 rotates the sample-carrier turntable 3.

Also connected across the 220 volt A-C lines 105-106 is a fullwave rectifier bridge circuit 107 which has its D-C output terminals connected across the latch-operating solenoid S2, of latching device 9 (FIG. 1).

The A-C lines 105, 106 are also connected in parallel to energize the inputs of a pair of monostable circuits No. 1 and No. 2, the functions of which will appear later.

The supply transformer secondary 103 delivers 24 volts energy which is applied to a full-wave rectifier bridge 110 having its positive output terminal grounded and its negative output terminal connected to a D-C supply line 111. This D-C supply line serves to energize a number of relay windings and other components which serve to control the automatic operation of the system in a manner that will stand out from the ensuing description of a test procedure.

It is assumed that the various units 11, 12, 13, 15 of the system shown in FIG. 1 are under power and that samples have been inserted on the turntable 3. The amplitude discriminator controls 25, 26 are adjusted in accordance with the element to be tested for in the samples as earlier explained it being first assumed that all twelve specimens or samples e1-e12 are to be tested for the proportions of a common element therein, say the proportion of sulfur in specimens of tire rubber. The voltage control 28 of the power supply unit 15 is also adjusted as to cut off all voltage peaks from ionization detector tube 2 corresponding to constituent elements of higher atomic numbers, and the current control 29 is adjusted to a suitable value such that the ionization detector 2 will reach saturation for a concentration of the tested element in the samples somewhat greater than the highest concentration values to be expected. The cover 4 is then lowered to sealing position, this action automatically moving the shutter 5 clear of the path of X-ray beam X from the X-ray tube 1 (as later described in detail).

After these preliminary operations have been performed, general switch 104 is closed. This energizes fan motor M3 to blow a stream of gas comprising 90% argon and 10% methane through the ionization detector tube 2. Power is simultaneously applied across each of the secondary windings 102 and 103. The voltage present across secondary 103 is rectified by bridge 110 and applies negative voltage (24 v.) to the D-C supply line 111. This has the following effects.

A relay winding R9 is energized through a circuit leading from D-C line 111 through winding R9 and thence to ground by way of two paths in parallel: the one through a reverser switch r7a in normal position, the other through a reverser switch r7b now in the position shown for reasons that will later appear. Energiza-

tion of relay winding R9 opens the normally-closed relay contacts r9a, thereby preventing energization of a stepping solenoid S3, and simultaneously closes the normally-open contacts r9b, preparing a path from stepping-switch arm 112 to ground. Stepping switch arm 112 cooperates with twelve switch segments Nos. 1 to 12 corresponding to the twelve indexing positions of the turntable 3.

A start-cycle switch K1 is now manually closed, energizing relay winding R1. This winding remains energized on release of the start-cycle switch through a holding circuit including normally-closed relay contacts r8a and relay contacts r1a, now closed due to energization of R1.

Energization of relay R1 closes contacts r1b thereby energizing vacuum valve solenoid S1 and vacuum pump motor M1, whereby vacuum valve 14 is shifted to disconnect the enclosure from atmosphere and connect it to the output of vacuum pump 10, and said pump is operated to evacuate the enclosure.

A delayed-action relay T is energized on energization of R1 by way of the contacts r3a and r3a, both in their normally closed positions, and contacts r1a now closed. After a determined delay period, 105 seconds in this example, contacts t associated with the delayed-action relay T are closed, whereupon a relay R3 is energized by way of said contacts t, normally closed contacts r8a and contacts r1a now closed.

On energization of R3, holding contacts r3b are closed to provide a holding circuit for R3 through r3b and normally-closed contacts r8b. Energization of R3 also closes normally open contacts r3c, thereby connecting ground by way of previously closed contacts r9b to the rotary switch arm 112.

Switch arm 112 is at this time engaging step contact No. 1, so that the ground potential is applied through said step contact and a diode 118 to a lamp L, shorting out a resistance 117 and permitting full illumination of the lamp. The ground potential on switch arm 112 is also applied through step contact No. 1 and a diode 119 to a terminal 120, and by way of a diode 121 to a terminal 122.

Terminals 120 and 122 constitute command inputs to the amplitude-discriminator and counter units 11 and 12. Application of ground potential to terminals 120 and 122 initiates the operation of the amplitude-discriminating and counting circuitry (not shown) in units 11 and 12, to count the pulses from detector output line 24 passed by unit 11, and having peak amplitudes determined by the presetting of controls 25 and 26, and for the time period determined by the presetting of control 27. On completion of the counting period, the count arrived at is recorded by the printing unit 13 together with the identification number of the sample just tested (i.e. sample No. 1) on a suitable medium such as a tape. Obviously the printing unit 13 may be replaced or supplemented with any other type of recorder, e.g. a card or tape perforating unit, or a display.

The printing unit 13, on having completed the printing operation, issues a command signal in the form of a voltage pulse applied to terminal 123, which energizes a relay winding 124 and closes associated contacts 125. This applies ground potential by way of contacts r3d, closed at this time, to input 115 of the monostable circuit No. 1.

Each of the monostable circuits No. 1 and No. 2 has power inputs 113 or 114 respectively, connected in parallel to the A-C lines 105-106 and has a ground connection 115 or 116. When both the power inputs and the ground line of either circuit are effectively connected, the circuit "flips" to its unstable state for a definite period, here about 1 second. In this state a voltage is applied to an output relay winding of the circuit, respectively R11 and R12, and associated contacts r11 or r12 are closed.

It will be noted that monostable circuit No. 2 has its power inputs 114 connected across A-C lines 105-106 by way of normally open contacts *r7b*, whereas circuit No. 2 has its power inputs 113 continuously energized from the A-C lines. Hence, the application of ground potential to input 115 causes the output relay winding R11 of the circuit to be energized for one second, with a corresponding closure of contacts *r11*. This in turn causes energization of relay winding R4 from D-C line 111.

Energization of R4 closes normally open contacts *r4a* whereby the D-C potential from rectifier bridge 107 is applied to energize the latch solenoid S2, thereby releasing the turntable indexing gear 8 for rotation. Energization of relay R9 likewise opens contacts *r4b*, preventing subsequent energization of stepping solenoid S3.

Latch solenoid S2, on being energized to release the index gear 8 and turntable for rotation, simultaneously reverses the position of switch *sw1*, thereby energizing relay winding R5.

Energization of relay R5 closes relay contacts *r5a* and *r5b*, applying alternating power from lines 105-106 across the A-C turntable motor M2. The motor starts revolving, carrying with it indexing gear 8, and turntable 3.

As the turntable 3 starts to revolve, a stop, not shown, carried by it acts on switch *sw2* energizes relay winding R7 after a short delay as determined by the time constant of resistor 126 and capacitor 127. Contacts *r7b* close, establishing a holding circuit for relay R7 through normally closed contacts *r8c* switch *r7a* reverses without immediate effect since contacts *r4b* are open.

After the time constant, about one second herein, of monostable circuit No. 1 has lapsed, its output relay R11 is deenergized opening contacts *r11* and deenergizing relay R4. Contacts *r4a* return to their normally open position deenergizing latch electromagnet S2. Therefore, as the turntable 3 reaches its next indexing position, the latch drops into the corresponding notch of the index gear 8, latching it in that position. Contacts *r4b* are returned to their normally closed position. Solenoid S3 is now energized through normally closed contacts *r9a* and *r9b* and switch contacts *r7a* now in reversed position owing to the energization of relay R7. Energization of solenoid S3 steps the rotary switch arm 112 to contact Nr. 2.

As latch solenoid S2 is deenergized and drops into latching engagement with index gear 8 at index position Nr. 2, it causes switch *sw1* to return to its normal position (shown), thereby energizing relay winding R9. Contacts *r9a* are opened, deenergizing stepping solenoid S3. Contacts *r9b* are closed, thereby applying ground potential through contacts *r3c*, now closed, to the stepping switch arm 112. Through stepping contact Nr. 2 this ground potential is applied by way of a diode 128 to one of a pair of contacts controlled by a manual test selector key K2. Key K2 and the similar keys K3-K12 associated with the respective stepping contacts Nos. 2 to 12, and only the first and last of which are shown, serve to preselect the specimen it is desired to analyze. Depression of any of these keys (which are provided with means not shown for latching them in depressed position) will ensure that the corresponding specimen *e2-e12* will actually be subjected to test when it reaches testing position. Where a key K2-K12 is not depressed, the amplitude-discrimination unit 11 will not be energized to gate pulses to digital counter 12, the printing machine 13 will be commanded to print a zero together with the number of the specimen, and the turntable will be indexed to the next position.

This provision for selecting the sample positions that are to be effectively subjected to the testing procedure constitutes an advantageous feature of the invention. It can often happen that it is only desired to test a small number of specimens, less than the full complement (herein twelve) the turntable 3 is adapted to receive. In

such cases it would clearly be a waste of time and power as well as a source of error, if the complete testing procedure, including the count of ionization pulses for the selected period, e.g. 30 seconds, were to be carried out for those indexed positions of the turntable at which no useful example is present. The means being described avoids this. It will be noted that no means are provided for omitting the test at indexed position Nr. 1, since presumably at least one sample is to be analyzed if the apparatus is being used at all.

Assuming then selector key K2 has been depressed, the ground potential from stepping contact Nr. 2 is applied through diode 128 and the closed contacts of key K2 to terminal 120, and through diodes 128-129 in series to terminal 122. When both these terminals are at ground potential, the units 11, 12 and 13 operate in the manner earlier described to count the discharge pulses gated by unit 11 for a selected period of time (e.g. 30 seconds), and print the count together with the specimen number (Nr. 2) on a record sheet. If however the ground potential signal from contact Nr. 2 is applied only to terminal 122 but not to terminal 120 due to selector key K2 not having been depressed, then the printing unit 13 is controlled through means not shown to print immediately a zero and the sample number upon the record sheet.

In either case on completion of the printing operation a command voltage signal is applied from printer 13 to terminal 123 energizing relay 124 to apply through contacts 125 a ground potential to the input 15 of monostable circuit No. 1.

This initiates a fresh stage of the cycle entirely similar to the one just described except that it will involve the sample position Nr. 3 of the turntable. The turntable 3 is thus indexed through its successive positions and any useful samples present therein are analysed and the corresponding counts are printed on the record sheet together with the identification numbers of the corresponding samples (as well as any other desirable indications). The repetitive operations involved in these cycle stages will

not again be described, and only the last stage occurring after the turntable 3 has rotated past sample position Nr. 12 will be discussed, since this involves the operation of the "end-of-cycle" monostable circuit No. 2.

The initial steps of the stage are as earlier described, monostable circuit No. 1 is energized for a period of one second, energizing relay R4 for a corresponding period. At the end of this period relay R4 is deenergized and its contacts *r4a* return to open condition, deenergizing latch solenoid S2. Contacts *r4b* are closed providing an energizing circuit for solenoid S3 through *r7a* in reversed condition and *r9a* in normally closed condition. Energization of solenoid S3 steps the arm 112 to position Nr. 1. As the turntable approaches its position Nr. 1 a stud provided on the index gear 8 actuates switch *sw2* to return it to its normal position shown, whereby ground potential is applied to input 116 of monostable circuit No. 2. Since at this time relay R7 is energized, circuit No. 2 is energized through contacts *r7c* from A-C lines 105-106 so that application of ground potential to its input 116 now energizes the monostable circuit No. 2 which delivers an output energizing relay winding R12. Contacts *r12* close, providing energization for relay R8.

Energization of relay R8 causes contacts *r8b* to open, deenergizing relay R3. Energization of relay R8 also causes opening of contacts *r8a*, deenergizing relay R1. Lastly energization of relay R8 causes opening of contacts *r8c*, deenergizing relay R7.

Deenergization of relay R1 opens the contacts *r1b*, cutting off the energizing circuit for vacuum pump motor M1 and solenoid S1. Hence the power is cut off from vacuum pump 10, and vent valve 14 is moved to a position in which it vents the interior of the enclosure under bell cover 4 to atmosphere. This will enable the bell cover to be easily lifted off the table 16.

Deenergization of relay R7 causes reverser contacts

r7a to return to their normal position shown deenergizing solenoid *S3*. Return of reverser contacts *r7a* to normal also energizes relay thereby *R9* opening contacts *r9a* and closing contacts *r9b*. However, both actions remain without immediate effect. Since relay *R3* is deenergized its contacts *r3c* are open and no ground potential is applied to the stepping switch arm *112*.

As the turntable *3* reaches indexing position Nr. *1*, latch *9* is allowed by deenergized solenoid *S2* to drop into the corresponding notch in the index wheel, latching the turntable at this position. The movement of the latch simultaneously moves the reverser switch *sw1* to its normal position, providing a circuit for the continued energization of relay *R9*, and cutting off the energizing circuit for relay *R5*.

Deenergization of relay *R5* opens its contacts *r5a* and *r5b*, cutting off the turntable motor *M2* from the power lines.

The bell-cover *4* can now be lifted off (since its interior has been vented to atmosphere as indicated above), and this action acts mechanically to interpose shutter *5* in front of the X-ray tube window *20*, permitting safe manipulation. The samples *e1-e12* can be removed from their mounts on turntable *3* and fresh samples inserted in their stead. Desirably, the turntable *3* is arranged for bodily removal from off the top of shaft *18*, and another identical turntable, not shown, carrying a complement of fresh specimens which have been manually inserted thereon by the operator during the automatic testing cycle described, can be substituted therefor on the shaft *18*. After fresh specimens have been positioned in either of the two ways just referred to, the bell cover *4* may be replaced, this moving shutter *5* clear of the X-ray tube window *20*. The cycle start key *K1* can then be depressed to initiate a fresh testing cycle. Meanwhile of course, the various controls previously discussed may have been readjusted if desired, and the test selector keys *K2-K12* reset.

Means are shown whereby the samples can be recycled for another round on the turntable *3* should it be desired to subject them to a further round of tests. When it is desired to do this, a "recycle" reverser switch *130* connected between relay winding *R8* and ground is thrown manually to its "Recycle" position. In this position ground is cut off from winding *R8* and connected instead through a connection *131* (only partly shown in the drawing) to one terminal of a neon lamp *132* the other terminal of which is connected to a D-C output terminal of rectifier bridge *107*. The lamp lights up to indicate the "recycle" condition. In this condition, it will be evident from the explanation given that the "end-of-cycle" monostable circuit No. *2* will remain inoperant to terminate the cycle. Specifically, relay *R8* will remain deenergized owing to its disconnection from ground, and hence relays *R3*, *R1* *R7* will remain energized. The indexing of the turntable and the testing procedure at each stage will then continue for another round, and for successive rounds so long as the recycle switch *130* is retained in recycle position.

In a preferred modification of the automatic control and programming unit partly illustrated in FIG. 4, means are provided for pre-selecting, in connection with each sample presented to testing position, not only the bare fact whether or not the sample is to be tested, but also the values of the parameters that are to be used in connection with each of the samples that are tested. These parameters may include as will be understood from previous explanations

Threshold voltage of the pulse peaks gated through amplitude-discriminator unit *11*;

Gate-width voltage of said gated pulse peaks;

Counting time in digital counter *12*:

High-tension voltage applied to X-ray tube *1*;

Current flow through X-ray tube *1*.

For the purposes of this detailed selection of the test parameters there are schematically shown in FIG. 4 five series of potentiometers, each series including twelve po-

tentiometers (not all shown). All the potentiometers of a first series, designated *TH1* to *TH12*, have one side of their resistors connected in common to a conductor *TH* which leads to a threshold voltage control circuit of the amplitude-discriminator unit *11*. All the potentiometers of a second series *GW1-GW12* have one side of their resistors connected by a common conductor *GW* to a gatewidth voltage control circuit of amplitude-discriminator unit *11*. The potentiometers of a third series *CT1-CT12* have one side of their resistors connected by a conductor *CT* to the count time control circuit of digital counter *12*. The potentiometers of a fourth series *XV1-XV12* have one side of their resistors connected by conductor *XV* to the high-voltage control circuit in the X-ray tube supply unit *15*; and the potentiometers of fifth series *XC1-XC12* have one side of their resistors connected by conductor *XC* to a current control circuit of unit *15*.

Correspondingly positioned potentiometers in all five series have their movable contact arms connected in series, by way of the interposed isolator diodes shown, to respective conductors leading to the twelve segmental contacts Nr. *1* to Nr. *12* respectively, of a rotary stepping switch *RS*. Thus, at each position of the rotary switch arm *112'* (stepped by solenoid *S3*) and hence at each testing position of turntable *3*, the ground potential present on switch arm *112'* will be applied to only a corresponding one out of the twelve potentiometers in each of the five series. It will be evident that by separately pre-setting the movable potentiometer arms it is possible to preselect the values of the test parameters used for each of the samples mounted on the turntable.

This makes it possible to test different samples mounted on the turntable *3* for different constituents. The samples may of course be specimens taken from the same or different batches of material, and the arrangement described provides the possibility, among many others, of accurately and quickly determining the proportions of a range of constituent elements in a batch of material in a single run of the apparatus described.

A practical form of construction of the sample changer and X-ray analysis assembly schematically described above in connection with FIGS. 1 and 2, will now be described with reference to the more detailed views of FIG. 5, 6 and 7.

The domed bell-like cover *4* is seen to be pivoted at one side to the table or baseplate *16* by means of the horizontal pivot *201*, and a handle *202* projecting from the opposite side of the bell cover *4* enables this cover to be conveniently rotated manually about its pivot for lifting it off the top of table or baseplate *16* and lowering it back into position in sealing engagement with the baseplate. The turntable *3* is seen to include a hub part *203* and a flanged rim part *204* removably secured thereto by means of one or more locator studs *205*. The hub *203* is keyed at *206* on the reduced upper part of vertical shaft *18* and secured thereon with a nut *207*, and is rotatably supported upon the baseplate *16* by way of an annular thrust bearing *208*. Shaft *18* includes an intermediate-diameter section which extends through a hat-shaped bearing member *210* mounted in a bore of the baseplate *16* and secured thereto with screws *211* extending through holes formed in the horizontal flange of the member *210* into holes formed in the undersurface of baseplate *16*. The said shaft section is supported for rotation in bearing member *210* by way of a conical roller thrust bearing *212* and an annular sealing gland *213* is lodged in a recess surrounding the shaft above the roller bearing *212*. An enlarged-diameter section *214* of shaft *18* abuts the lower inner race of thrust bearing *212* and cooperated with nut *207* to retain the parts in assembly.

Spacer posts *215* have their upper threaded ends screwed into holes formed in the flange of bearing member *210* and project downward therefrom to support a horizontal motor-mounting plate *216* secured to the low-

er ends of the posts with screw studs. The motor M2 serving to drive the shaft 18 and turntable 3 is attached by means not shown to the under side of plate 216 and the motor output spindle 217 projects upward through a central hole in said plate. The motor spindle 217 has a disk-like friction coupling member 218 non-rotatably secured around it a short distance above mounting plate 216 by means such as a grub screw engaging the spindle.

The indexing wheel 8 is in two parts, including a hub part 219 and a peripheral part 220 secured thereto with screws. The peripheral part 220 has twelve notches such as 221 formed around its outer periphery for the purposes of the indexing function. The hub part 219 of indexing wheel 8 has a central aperture which is non-rotatably slidable around the lower end of a stud member 222 which projects from the lower end of shaft 18 and forms a unitary extension of said shaft. A compression spring surrounding a central boss of part 219 presses said part down so that its under surface frictionally engages the friction surface of coupling disk 218. The upper end of spring 223 is abutted by the lower end of an inverted cup-shaped member 224 slidable around stud member 222 and abutted at its upper surface against a nut adjustably screwed on a threaded section of stud member 222 in order to control the pressure of frictional engagement of the friction coupling.

The casing of latch control solenoid is supported from stationary structure not shown in fixed relation with motor M2 at one side of index wheel 8. The latching armature 226 cooperating with the solenoid has a tapered latching nose insertable into any one of the notches 211 by the action of a spring on deenergization of the solenoid.

The microswitch sw1 is secured to the casing of solenoid S2 at the under side thereof and its switch actuator element projects upwards as shown into the path of an annular rib surrounding the latching nose of armature 226 so as to be actuated on deenergization of the solenoid as earlier explained herein.

The microswitch sw2 is supported through a bracket from the upper side of the solenoid casing and its actuator element projects downward so as to be actuated by a stud 228 projecting upward from the periphery of the indexing gear 8. It will be recalled that switch sw2 is to be actuated by stud 228 once per revolution of the indexing wheel and turntable 3 so as to be returned to its normal position in order to initiate end-of-cycle functions. Accordingly stud 228 is positioned at a suitable setting on indexing member 220 between the notches 221 which correspond to sample position No. 12 and sample position No. 1.

Returning to the turntable 3, the rim member 204 thereof has twelve pairs of radially spaced holes 229 formed around its flanged periphery for the affixing of twelve sample mounts such as 230 thereto by means of studs inserted into said holes. Only one sample mount is shown. The sample mounts are small rectangular frame members conveniently made of an epoxy resin (such as "Araldite"), having means for removably securing therein the rectangular samples such as e1, which herein are 3 millimeter thick test pieces of rubber to be analyzed for sulfur content. The samples are adapted to be supported in the mounts 230 with an outer face thereof accurately located against a locating surface surrounding the inner periphery of a rectangular window formed in the sample mount. A retainer block 232 of suitable material and centrally perforated for the escape of entrapped air, it can be blocked in position behind the specimen e1 by means of a set screw 233 threaded into the top of the mount.

As earlier indicated a convenient practical procedure is to remove the turntable 3 with all the samples thereon bodily from the apparatus and substitute another turntable with fresh samples prepared at a separate station. This is greatly facilitated by the construction shown wherein the rim part 204 of the turntable can be lifted off the

hub part 203 by means of the grips 244 projecting therefrom, and can be reinserted in a prescribed setting relative to the hub owing to the provision of the locator pin or such as 205.

5 The movable safety shutter 5 which serves to mask the X-ray beam when the bell cover 4 is lifted from its operative position as earlier described, is best seen in FIG. 7. The shutter 5 is in the form of a rigid strip of suitable material opaque to X-rays and is pivoted at an intermediate point about a horizontal pivot 245 on a suitable support upstanding from baseplate 16. The support may constitute the casing of counter tube 2. A tension spring 246 has its ends attached to the inner extremity of shutter 5 and to a suitable anchor point on the baseplate so as to urge the shutter to its masking position, shown in dot-dash lines, in which it masks the window 20 of the X-ray tube 1 through which the X-ray beam issues. The outer end of shutter 5 beyond pivot 245 carries a laterally projecting bracket 248 the upper surface of which is engageable by an actuator lug 249 projecting downward from an arm 250 supported from a sidewall of cover 4. As shown, in the normally lowered position of cover member 4, the lug 249 acts to depress the bracket 248 and thereby move the shutter 5 to its upper position shown in full lines against the tension of spring 246. In this position shutter 5 is clear of the X-ray beam. When however the domed cover 4 is lifted the lug 249 disengages the flange 248 and the shutter returns under the bias of spring 246 to the lowered position shown in 10 dot-dash lines, in which it masks the beam issuing from window 20 and thus permits manipulation without danger of irradiation to the operator.

15 Both the X-ray generator tube 1 and the ionization counter 2 are generally standard pieces of equipment manufactured and sold by the assignee, Compagnie 20 Générale de Radiologie. More specifically the X-ray tube 1 used was similar to the tube embodied in the assignee company's X-ray analysis unit sold by the trade name "Cristallobloc" in which the cathode was angularly displaced 6° for convenience. The ionization counter 2 was a modified form of the continuous gas-flow proportional counter marketed as "DM. 160."

25 It will be noted especially from FIG. 6 that the geometry of the X-ray tube 1 and ionization counter 2 as 25 mounted with respect to the test sample e1 in testing position is so arranged as to provide an extremely compact disposition with the sample positioned very close to the windows of the tube and counter, and in such an angular relationship thereto as to be seen under relatively large, 30 equal mean solid angles both from the X-ray tube 1 and the ionization counter 2.

Example

35 The non-dispersive X-ray analysis apparatus substantially in the form disclosed with reference to FIGS. 5-7 was developed for use as a production-inspection appliance in the workshops of a tire manufacturing plant, the Compagnie des Pneumatiques Michelin, Clermont-Ferrand, France, for the determination of sulfur content in 40 the rubber stock. The sulfur content could vary over a range of from 1% to 6% and the relative accuracy of the determination specified was to within $\frac{1}{100}$ of the sulfur content. The rubber stock contained substantial amounts of zinc oxide. The rubber specimens used were rectangular 45 strips 20 by 30 millimeters ranging in thickness from 1 to 3 mm.

The amplitude-discriminator 11 and digital counter 12 (FIG. 2) were embodied in a unit marketed as the "ANC 660 Spectroscaler" by Ateliers de Constructions Electriques de Charleroi, S.A., Charleroi (Belgium), an affiliate of the assignee company. The printing unit 13 used 50 was the above-identified manufacturers' "M.A.I. 100."

The enclosure was evacuated to a pressure of 10^{-2} torr.

55 The X-ray high-voltage supply unit 15 was regulated

to an output voltage constant to within 10^{-3} and was set to 6 kilovolts and 1 ma, reasons earlier indicated.

The counter was supplied under a voltage of 1350 volts, and the pulses were passed through an amplifying chain of 4 db attenuation and providing a gain of 50 in the preamplifier stage and 10,000 in the amplifier stage.

An initial calibration of the apparatus was carried out by using a sample of graphite containing 5% sulfur, and the curve shown in FIG. 8 earlier referred to was plotted. It was thus found that the sulfur peak could be satisfactorily gated by adjusting the controls 25, 26 of the amplitude discriminator unit 11 to a voltage gating threshold of 46 volts and a gate width of 18 volts, as shown in the graph.

To calibrate the system over the entire range of sulfur concentrations specified, seven specimens of known sulfur content were passed through the apparatus and the average number of discharge pulses per second over thirty-second periods as indicated by the digital counter unit 12 for each specimen were recorded. The results are given in the following table:

Sample No.	S percent	Discharge pulses per second
1	1.02	71,268
2	1.33	162,081
3	2.80	127,540
4	3.65	146,550
5	4.51	161,049
6	5.35	167,698
7	6.19	178,214

These results are plotted in the graph of FIG. 9 with sulfur content percent in abscissa and pulses per 30 seconds in ordinates.

The curve shows a good degree of regularity and a slope (sensitivity) steep enough to provide the specified degree of relative accuracy with counting times not exceeding 30 seconds. Higher accuracies can of course be achieved simply by increasing the counting time beyond thirty seconds. The results were found to be relatively unaffected by the surface condition of the samples. On the other hand, the precise positioning of the tested sample surface with respect to the X-ray tube and the ionization counter against the locating surface of sample mounts 230 has been found to be of considerable importance especially in the case of thin samples.

Of the many possible variations and modifications conceivable by those familiar with the art without departing from the scope of the present invention, one modification will be specifically referred to herein because of its potential importance. This concerns the possibility of testing a sample while positioned at the analyzing station for two (or more) different constituent elements simultaneously. It will be evident that the programmer circuitry of FIG. 3 and/or FIG. 4 can be modified in simple ways (for example by providing therein an additional rotary switch similar to the one shown in FIG. 2 or 3, and having its switch arm rotated step-by-step by means of solenoid S3), so that the amplitude-discriminator unit 11 will simultaneously gate through different gating channels thereof two (or more) pulse trains from ionization detector output lead 24 having different, preselected, peak amplitude values. These pulse trains of different amplitude can be directed to separate digital counters such as 13 (or to different counting channels of a common digital counter) in order to indicate simultaneously the amounts of different, selected, constituent elements present in the sample.

What I claim is:

- Apparatus for X-ray analysis comprising:
an X-ray generator;
a sample carrier indexable to present each of a series of samples to an analyzing station adjacent the generator to be irradiated with an X-ray beam;
means for indexing the sample carrier;
an ionization detector positioned adjacent the analyzing station to be irradiated with a secondary beam re-

emitted by the sample and producing ionization discharge voltage pulses corresponding in peak amplitude to various constituent elements of the sample and at rates corresponding to the proportions of said elements in the sample;

5 electronic gating and counting means connected to receive said pulses from the detector and to count those pulses having peak amplitudes in a selected range;
means operative on termination of a count by said electronic means to advance the sample carrier to present a next sample of the series to the analyzing station;
and presetable adjusting means associated with said indexing means and said X-ray generator for adjusting the voltage and current of the generated X-ray beam to desired values in each of the indexed positions of the sample carrier.

2. Apparatus for X-ray analysis comprising:

an X-ray generator;
a sample carrier indexable to present each of a series of samples to an analyzing station adjacent the generator to be irradiated with an X-ray beam;
means for indexing the sample carrier;

an ionization detector positioned adjacent the analyzing station to be irradiated with a secondary beam re-emitted by the sample and producing ionization discharge voltage pulses corresponding in peak amplitude to various constituent elements of the sample and at rates corresponding to the proportions of said elements in the sample;

30 amplitude discriminating means connected to receive said pulses from said detector and to gate only those pulses having peak amplitudes in a selected range to an output of said amplitude discriminating means;
digital counter means connected to said output to count the pulses gated thereby;

means operative on the termination of a count by said digital counter to advance the sample carrier to present a next sample of the series to the analyzing station;

35 and presetable adjusting means associated with said indexing means and said digital counter means for adjusting the counting time over which the gated pulses are counted in each of the indexed positions of the sample carrier.

40 3. The apparatus claimed in claim 2, including recording means connected to the digital counter for recording the count obtained thereby, and including means responsive to the termination of a recording operation to advance the sample carrier to present a next sample of the series to the analyzing station.

45 4. The apparatus claimed in claim 2, including means presetable for preventing the digital counter from making a count for any non-indexed samples of the series.

50 5. Apparatus for X-ray analysis comprising:
an X-ray generator;
a sample carrier indexable to present each of a series of samples to an analyzing station near the generator to be irradiated with an X-ray beam;
means for indexing the sample carrier;

55 an ionization detector positioned near the analyzing station to be irradiated with a secondary beam re-emitted by the sample and producing ionization discharge voltage pulses corresponding in peak amplitude to various constituent elements of the sample and at rates corresponding to the amounts of said elements in the sample;

60 amplitude discriminator means connected to receive said pulses and adjustable to gate only those pulses having peak amplitudes in a selected range corresponding to a selected element, to an output of the amplitude discriminator means;

65 digital counter means connected to said output to count the gate pulses;
means operative on termination of a count by said digital counter to advance the sample carrier to pre-

sent a next sample of the series to the analyzing station; and presettable adjusting means connected to the indexing means and the amplitude discriminator for presetting the amplitude range of the pulses gated thereby to a selected range in each of the indexed positions of the sample carrier.

6. Apparatus for X-ray analysis comprising:
a sealable enclosure;
an X-ray generator in the enclosure;
a sample carrier in the enclosure intermittently displaceable to present each of a series of samples to an analyzing station to be irradiated with an X-ray beam from the generator;
an ionization detector positioned in the enclosure to be irradiated with a secondary beam emitted by the sample and producing voltage pulses corresponding in peak amplitude to various constituent elements of the sample and at rates corresponding to the proportions of said elements in the sample;
electronic analyzer means connected to the detector for counting the pulses in a selected range of peak amplitudes;
a source of vacuum connectable with the enclosure and means for venting the enclosure; and
an electric controller unit energizable to initiate a testing cycle, said unit including:
means operative at the start of a cycle to connect the enclosure with the vacuum source, means connected with the sample carrier for intermittently displacing the sample carrier to present each sample of the series in succession to the analyzing station, means connected with the electronic analyzer means to energize same for counting said pulses during presentation of each sample, and means operative after presentation of the last sample of the series to disconnect the enclosure from the vacuum source and vent the enclosure.

7. The apparatus claimed in claim 6, wherein said controller unit includes a recycle control operable to prevent disconnection and venting of the enclosure after presentation of said last sample and to initiate a further testing cycle.

8. The apparatus claimed in claim 6, including a cover member for said enclosure movable between an open and a sealing position, a movable shutter in the enclosure movable between a position in which it masks the X-ray beam from the generator and a clear position, and means actuated on movement of the cover member to open position to move the shutter to masking position and actuated

on movement of the cover member to sealing position to move the shutter to clear position.

9. The apparatus claimed in claim 6, including presettable means in the controller unit connected with said analyzer means for selecting the amplitude range of the pulses counted thereby during presentation of each sample.

10. Apparatus for X-ray analysis comprising:
an enclosure connectable to a vacuum source;
an X-ray generator in the enclosure having a removable cover;
a turntable in the enclosure carrying a series of samples spaced around its periphery and intermittently rotatable to present each sample in succession to an analyzing station near the generator to be irradiated with an X-ray beam;
a detector positioned in the enclosure to be irradiated with a secondary beam emitted by the sample and producing voltage pulses corresponding in peak amplitude to various constituent elements in the sample;
electronic analyzer means connected to the detector for counting the pulses in a selected range of peak amplitudes;
means operative on termination of a count to advance the turntable to present a next sample to the analyzing station;
means for connecting said enclosure with said vacuum source at the start of a testing cycle and means for venting the enclosure at the termination of a testing cycle, whereby the cover can be removed; and
removable shutter means in the enclosure and means actuated on removal of the cover to move said shutter means to a position in which it masks the X-ray beam from said generator to permit safe manipulation in the enclosure after removal of the cover.
11. The apparatus defined in claim 10, including means for bodily removing at least part of said turntable together with the tested samples carried thereby from out of the enclosure after removal of the cover, and for bodily inserting another turntable carrying further samples to be tested.
